UNITED STATES PATENT OFFICE.

MILES W. HAWKS, OF HAYESVILLE, OHIO.

DOOR-OPERATING DEVICE.

Application filed May 15, 1926. Serial No. 109,363.

This invention relates to closure operators and pertains particularly to a device for opening and closing the doors of buildings such as garages, barns, or other structures having sliding doors.

The primary object of this invention is the provision, in a manner as hereinafter set forth, of a structure designed to enable one to easily and quickly cause one or a pair of sliding doors to move in such a manner as to uncover or cover an entrance opening, means being provided for the performance of this operation from a point in front of the doorway, as from the seat of an automobile or other vehicle desiring to pass through the entrance.

Another object of the invention is the provision, in a manner as hereinafter set forth, of a closure operating structure adapted to be controlled from a remote point, and having automatically operating means for catching and holding the doors in their opened or closed position.

Another and final object of the invention is the provision, in a manner as hereinafter set forth, of a closure manipulating mechanism of simple, strong and durable design, constructed to withstand exposure to the elements without injury, easy to manipulate and comparatively inexpensive to manufacture and install.

The invention will be best understood from a consideration of the following detailed description taken in connection with the accompanying drawings forming a part of this specification, with the understanding that the invention is not confined to any strict conformity with the showing of the drawings but may be changed and modified so long as such changes and modifications mark no material departure from the salient features of the invention as expressed in the appended claims.

In the drawings:—

Figure 1 shows a building in front elevation having sliding doors and provided with the mechanism embodying this invention.

Figure 2 is a vertical sectional view taken upon the line 2—2 of Figure 1.

Figure 3 is a horizontal sectional view taken on the line 3—3 of Figure 1 and,

Figure 4 is a section taken upon the line 4—4 of Figure 1.

Referring now to the drawings in detail wherein like numerals of reference indicate corresponding parts throughout the several

views, the front wall of a building such as a barn or garage is indicated by the numeral 1. The usual entrance opening 2 is formed through this wall and this entrance is closed under normal conditions, by the pair of door structures 3, the inner longitudinal edges of which are in abutting relation when the entrance is closed.

Secured centrally to the front wall 1 above the doors 3 is a vertically arranged elongated block or plate 4. Upon each side of the block 4, extending parallel therewith and in spaced relation therewith is an elongated guide bridge 5 the ends 6 of which are secured to the face of the wall 1 adjacent the ends of the block 4. As is clearly shown in Figure 2 these bridges 5 extend a substantial distance forwardly of the forward face of the block 4.

Pivotedly secured to each side of the block 4 is a latch member indicated generally by the numeral 7. Each of these latch members comprises a lower free portion 8, the upper obtusely angled portion 9 and the terminal stop portion 10 which extends outwardly substantially at right angles to the portion 9. The portion 9 is obtusely angled with respect to the portion 8 and at the point of joinder of these two portions, the pivot member 11 extends through the device into the side of the supporting block 4. The front edge of each of the latch members 7 has extending outwardly therefrom, also adjacent the point of joinder of the two portions 8 and 9, the catch finger 12. As is shown in Figure 4 the width of the two portions 8 and 9 is substantially the same as the width of the side of the block 4 to which the latch is fixed, thus causing the finger 12 to project beyond the front face of the block 4, at all times. The stop portion 10 of each latch also extends a substantial distance beyond the face of the supporting block 4 as is also clearly shown in Figure 4.

Pivotedly mounted upon each of the corner posts 13 of the building structure, by means of the supporting pivot bolts 14 is a swinging track arm 15. Each of the arms, as shown, is pivoted at its outer end and from this pivoted outer end each arm tapers toward its inner end, which inner ends are extended beneath the bridges 5 and overlie in spaced end opposed relation, the block 4. As is shown in Figure 1, the arms 15 are so formed that when they are in the hori-

zontal position shown with the lower edges resting upon the lower part of an adjacent bridge structure 5, the top edge of each arm inclines downwardly from the outer 5 pivotal point to the inner end thereof, the lower edge of each arm being substantially horizontal.

Each of the arms 15 has extending from the pivoted end thereof the outwardly and 10 upwardly extending counter weight arms 16, these counter weight arms being relatively short as shown and forming an obtuse angle with respect to the adjacent track arm.

Each of the doors 3 has extending upwardly from the top thereof the supporting straps 17, the upper ends of which straps are turned back upon themselves in spaced relation to the body and have pivotally secured between the back turned portion and the 20 body thereof the grooved supporting rollers 18. These grooved supporting rollers 18 rest upon the top edge of the adjacent track arm 15 and slidably support the doors upon these track arms. As is shown, one of the 25 supporting straps 17 is of slightly greater length than the other strap of the same door, to compensate for the inclination of the supporting edge of the track arm from which the door is suspended, thus insuring 30 the level positioning of the doors.

Secured in superposed relation in the face of the front wall 1 of the building, directly above and upon the longitudinal center of the block 4, is a pair of supporting eyes 19. 35 Mounted upon the face of the wall 1 between the supporting eyes 19 is a bracket 20 carrying a pulley roller 21.

Engaged in the eyes 19, are the down-turned ends 22 of supporting arms 23, which arms extend outwardly and downwardly from the face of the building and are joined together at their outer ends by the yoke 24 in which yoke a pulley member 25 is pivotally mounted.

Engaged through the apertures 26 formed in the inner free end of the track arms 15 are short ropes or cables 27 which are joined at their upper ends as at 28, to one end of a pull cable 29. This pull cable extends upwardly over the pulley 21 and outwardly between the arms 23 to and over the pulley 25 carried at the forward outer end of the arms. A hand grip 30 is carried at the free outer end of the pull cable 29.

In operating the mechanism embodying this invention, when it is desired to open the doors, the pull cable 29 is grasped at the free outer end 30 and pulled downwardly. This pull of the cable raises the free inner ends of the track arms 15, assisted by the counter weights 16 at the outer ends of the arms. The upward inclination of the track arms 15, in the position indicated in dotted lines in Figure 1, will cause the doors 3 to move by gravity apart and toward the side

of the building. When the free inner ends of the arms are raised to the limit of their upward movement, they will pass over and be engaged at the under edge by the latch finger 12 of the catches 7. The pull cable 29 can then be released and the doors will remain in open position. When it is desired to close the doors, a slight upward pull of the free ends of the arms 15 by means of the cable 29, will cause the arms to bear 75 against the angled portions 9 and strike the extension 10 of the latch member causing the latch to swing upon the pivot 11 until, by overbalancing the upper end of the latch, the portion 9 will fall back against the wall 80 1 and remain in this position until the arms drop past the finger 12, after passing the finger 12 the arms will strike the outwardly projected portion 8 and again overbalance the latch, swinging it to the position shown 85 in Figure 4. It will be readily seen that when the track arms are dropped to the position shown in full lines in Figure 1, after the doors have been in open position, the inner supporting pulley of each door 90 will fall a considerable distance beneath the level of the outer supporting pulley as the outer supporting pulley is raised upon the counter weight portions 16 of the arms. This will cause gravitational force to act 95 upon the doors and cause them to move inwardly to the closed position shown.

From the foregoing description it will be readily seen that a very serviceable, simple and efficient door closing mechanism has been constructed which can be operated with little effort and is absolutely positive in its action.

Having thus described my invention what I claim is:—

1. A sliding door operating mechanism, comprising a track rail arm adapted to be pivotally secured at one end, an obtusely angled, upwardly inclined counter-weight arm extending from said pivoted end, a guide bridge overlying the free end of said rail arm, pivoted latch means mounted adjacent said bridge and adapted to engage the free end of said rail arm when raised, to hold the same in raised position, and roller door supporting elements mounted to move along said arm by gravity when the arm is raised, one of said elements running onto said inclined arm and acting to start the door to close the same when the track arm is lowered.

2. A door closure mechanism, comprising a pair of end opposed aligned track arms each pivotally mounted at its outer end, a guide bridge overlying the inner end of each arm, roller door supporting elements mounted to move along each arm, means attached to the inner end of each arm for raising the same, and a latch member pivotally mounted upon the inner side of each bridge behind

each arm and adapted to engage and hold said arm in raised position.

3. A door closure mechanism, comprising a pair of end opposed aligned track arms 5 each pivotally mounted at its outer end, a guide bridge overlying the inner end of each arm, roller door supporting elements mounted to move along each arm, means attached to the inner end of each arm for raising the same, a latch member pivotally mounted upon the inner side of each bridge behind each arm and adapted to engage and hold 10 said arm in raised position, and a counter-weight arm extending at an angle from the outer end of each track arm, upon which a roller element is adapted to pass when the track arms are raised, said arms when raised to the proper point acting upon said 15 latch members to release the same to allow the arms to be lowered.

4. A door closure mechanism, comprising a pair of end opposed aligned track arms each pivotally mounted at its outer end, a

guide bridge overlying the inner end of each 20 arm, roller door supporting elements mounted to move along each arm, means attached to the inner end of each arm for raising the same, a latch member pivotally mounted upon the inner side of each bridge behind 25 each arm and adapted to engage and hold said arm in raised position, and a counter-weight arm extending at an angle from the outer end of each track arm, upon which a roller element is adapted to pass when the track arms are raised, said counter-weight arms raising upon the lowering of the track arms, to start the closing movement of the 30 door supporting elements.

In testimony whereof, I affix my signature hereto.

MILES W. HAWKS.
